COKE OVEN CONSTRUCTION

Maurice D. Curran, Glendale, Mo., assignor to Tar & Petroleum Process Company, Chicago, Ill., a corporation of Illinois

Application August 8, 1936, Serial No. 94,916

8 Claims. (Cl. 202—102)

The present invention relates to coke oven construction.

In the manufacture of coke it is sometimes desirable to use gas of relatively low B. t. u. value, such for example as blast furnace gas or producer gas, in which case it is usual to preheat it before it reaches the combustion chambers of the coke ovens. This preheating is preferably done by means of regenerators cooperatively associated with the ovens. The utilization of the preheaters for preheating this low value gas has the serious objection that it complicates the brickwork construction of the ovens and also adds considerably to the expense of the installation. When leakage occurs, as for example when cracks in the brickwork develop, further difficulties are encountered.

It has been found from experience that the pier walls of coke ovens absorb considerable heat from the adjacent flues, so much so that it is difficult to keep the brickwork of said piers from softening unless the very highest grade of refractory is used. Certain examples of high-grade refractory have such different coefficients of expansion from the rest of the oven that expansion strains present serious problems under these conditions. Reference is made to applicant's co-pending application Serial No. 94,917.

An object of the present invention is to provide a construction for coke ovens or the like in which the low B. t. u. gas is conducted through the pier walls to perform the dual function of cooling said walls and preheating said gas.

A further object is to provide a construction for coke ovens or the like in which the pier walls are cooled and the gas is preheated without the attendant difficulty of cooling the combustion flues of the oven.

Further objects will appear as the description proceeds.

Referring to the drawings—

Figure 1 is a vertical sectional view taken through a battery of coke ovens embodying the principles of the present invention;

Figure 2 is a sectional view taken at right angles to the view shown in Figure 1, Figure 2 being taken along the plane indicated by the arrows 2—2 of Figure 1;

Figure 3 is a sectional view taken along the plane indicated by the arrows 3—3 of Figure 1; and

Figure 4 illustrates a detail of construction.

Referring first to Figure 1, the numerals 10—10 indicate a plurality of coke ovens arranged side by side to form a battery. Each of said ovens

comprises a coking chamber 11 having a horizontal floor 12 and a roof 13. The coking chambers are commonly of a height relatively small compared to their width and length. Each of said chambers will be provided with end doors 5 15 and 16 through which the resulting coke may be pushed out of the coking chambers. Each of said chambers will also be provided with means (not shown) for charging coal and means for withdrawing vapors and gases. 10

According to usual practice in the Knowles type of oven, such as that illustrated in the drawings, a plurality of heating flues 17—17 are disposed below the floor 12 of each oven in thermal communication with said floors. Said flues are defined by the horizontal wall 18 and the vertical walls 19—19. Said horizontal wall 18 provides openings 20—20 from the heating flues 17 to the space below said flues, said openings 20—20 being located adjacent to the end walls of each of 20 the ovens. Disposed medially of each of the ovens is the vertical wall 21 extending transversely of each of said ovens. Each of said medial walls 21 extends downwardly from the horizontal wall 18 to the foundations of the corresponding 25 oven and divides the space below the wall 18 of each oven into two regenerative chambers, indicated by the numerals 21a and 21b. Extending from each end wall of each oven is the horizontal partition wall 22 disposed below and in spaced 30 relationship with the wall 18. Each of said walls 22—22 at the region adjacent to the vertical wall 21 has an aperture 23 providing communication between the region above and the region below the corresponding wall 22. Expressed in other 35 language, the horizontal wall 22 at each end of each oven provides at U-shaped passageway or a hairpin passageway from a region at the bottom of the oven adjacent to the end wall thereof to the medial region of the oven and back adjacent to the end wall where communication is had through the apertures 20 to the heating flues 17. According to the usual practice, waste heat tunnels 24 are provided at the ends of the ovens, that is—extending longitudinally along the pusher 45 side and the coke side of the battery of ovens. Downtakes 25—25 provide communication from the regenerative chambers at each end of each oven with said waste heat tunnels.

The numeral 26 indicates generally a conduit 50 extending through each of the pier walls 14. According to the illustrated embodiment of the present invention said conduit 26 is made up of two parallel branches, indicated by the numerals 26a and 26b. Said branches 26a and 26b are lo- 55

cated at a point at which the gas flowing there-through will absorb sufficient heat from the material of the pier wall to protect said pier wall from overheating, but at the same time will not 5 reduce the temperature of said pier wall enough to affect the coking temperatures of the floors of the ovens adjacent to said pier walls. To this end the upper branch 26a of the conduit 26 is preferably, though not necessarily, located below 10 the level of the flues 17-17.

Referring now to Figure 4 for a preferred detail of construction of each of the branches of the conduit 26, the branch 26a is indicated in the form of a round pipe encased between a pair 15 of preformed blocks 27-27 having substantially semi-cylindrical grooves facing each other for receiving said pipe 26a. The brickwork of the pier wall is indicated by the numerals 28-28. By reason of the use of the preformed blocks 20 27-27, said blocks may fit closely around the pipe 26a and at the same time the removal of the pipe in case of necessity and the replacement thereof will be relatively simple. Inasmuch as the brickwork adjacent to the conduit 26 will in 25 service be above red heat, heat will be transferred to the pipe 26a largely through radiation thereof, emphasizing the desirability of making the space between the pipe 26a and the material surrounding said pipe as small as possible consistent with the ease of moving said pipe when 30 necessary. By reason of the illustrated construction, the pipe 26a may be of relatively large size without sacrificing ample support for the corresponding pier wall on each side of said pipe. 35 Any preferred means, may be used if desired to render turbulent the flow of gas through each of the branches of the conduit 26.

The present invention contemplates a construction eliminating the use of valves in positions where they are likely to attain high temperatures. The numerals 29 and 30 indicate seal 40 pots located at the two sides of a battery of ovens. Said seal pots are adapted to contain liquid, such for example as water, oil or tar. Communicating 45 with each of said seal pots is a pipe 31 connecting with a gas manifold 32, which gas manifold 32 is adapted to deliver gas through the gas inlets 33 to the heating flues 17 of the ovens at the two ends thereof. Said pipe 31 at each side of the 50 battery of ovens extends to a region adjacent to the bottom of its corresponding seal pot 29 or 30. Communicating with the top region of each seal pot 29 or 30 is the pipe 34 connecting with the branches of the conduit 26 at the two sides of 55 the battery of ovens. Gas supply headers 35-35 communicate with said pipes 34-34. Cooperatively associated with each of the seal pots 29 and 30 is a pipe 36 for selectively draining one or the other of said seal pots 29 and 30 and selectively filling said seal pots.

In installations in which the gas passing from the pipes 34-34 through the pier walls 14 do not absorb the desired amount of heat from said pier walls, the gas from said pipes 34-34 may be 60 directed through passageways in intimate thermal communication with the regenerative chambers 21a and 21b. The drawings show looped passageways 34a forming part of the conduit 26 for conducting gas from each pipe 34 at each side 65 of the battery to the end region thereof, back to the sides of the battery, whence the gas passes longitudinally of the pier walls. Said passageways 34a have been illustrated in the brickwork of the oven, but of course they may be located at other places in thermal communication with

the regenerative chambers 21a and 21b. The passageways 34a at each side of the battery may be in parallel or in series relationship with each other, as preferred.

The mode of operation of the above described embodiment of the present invention will be clear without detailed explanation. When it is desired to use gas of low B. t. u. value, such gas is preheated by passage through the passageways or conduit 26 in the pier walls, thereby accomplishing the dual function of holding down the temperature in said walls and heating said gas. When it is desired to deliver gas to the right-hand side of the battery of ovens as the parts are viewed in Figure 2, the right-hand seal pot 30 10 will be emptied, gas will be admitted to the left-hand header 35, and said gas will pass through the left-hand looped conduit 34a, thence in parallel through the passages 26a and 26b through the right-hand looped conduit 34a to pipe 34 and 15 seal pot 30 to the gas manifold 32 at the right side of the installation to the gas inlets 33. At this point it will mix with the air, which air is delivered from the right-hand tunnel 24 through the right-hand regenerative chamber 21b and 20 opening 20 into contact with the gas from the right-hand inlet 33. Hot waste gases from the flues 17 will pass outwardly through the left-hand regenerator to the left-hand gas tunnel 24. At this time the left-hand seal pot 29 is filled 25 with liquid and communication therethrough is closed. Upon reversal of the oven the left-hand seal pot 29 will be emptied and the right-hand seal pot 30 will be filled with liquid. At this time communication will be cut off between the source 30 of gas supply and the left-hand gas main 35. Under these conditions communication will be opened from the gas supply through the right-hand gas header 35, and gas will flow through the right-hand looped conduit 34, thence in a left- 40 hand direction in parallel through the passages 26a and 26b to the left-hand looped conduit 34 through the seal pot 29 to the manifold 32 at the left-hand side of the installation. At this point the gas for combustion will mix with air 45 delivered from the left-hand tunnel 24 and left-hand regenerative chamber 21a. Under these conditions the waste gases will flow from the flues 17 through the right-hand regenerator to the waste gas tunnel 24 at the right side of the installation. 50

By reason of the present invention, gas may be preheated and in being heated take away the excess heat units from the pier walls, thereby protecting the pier walls. Moreover, the hot gas 55 can be effectively controlled without the provision of valves in regions where they are likely to become very hot. It will be understood, of course, that when it is not desired to preheat the gas the branches of the conduit 26 may be used 60 merely for ventilation, air being delivered through said conduit, being speeded up by any preferred means.

Though a preferred embodiment of the present invention has been described in detail, many 65 modifications will occur to those skilled in the art. It is intended to cover all such modifications that fall within the scope of the appended claims.

What is claimed is—

1. In combination, a battery of ovens, pier walls between the ovens of said battery, each of 70 said ovens having a horizontal floor and heating flues below said floor, said flues extending throughout the length of said floor, gas supply 75

means at the two ends of said ovens, said pier walls being provided with passageways extending longitudinally thereof, gas inlet means communicating with said flues at the two ends of said ovens, air supply means communicating with said flues adjacent to said gas inlet means, and valve means for selectively controlling the flow of gas from said gas supply means through said passageways to the gas inlet means at the other end of 10 said ovens.

2. In combination, a battery of ovens, pier walls between the ovens of said battery, each of said ovens having a horizontal floor and heating flues below said floor, said flues extending 15 throughout the length of said floor, gas supply means at the two ends of said ovens, said pier walls being provided with passageways extending longitudinally thereof, gas inlet means communicating with said flues at the two ends of said ovens, air supply means communicating with said flues adjacent to said gas inlet means, and valve means for selectively controlling the flow of gas from 20 said gas supply means through said passageways to the gas inlet means at the other end of said ovens, said passageways being located at a 25 level below said floor.

3. In an oven, in combination, a coking floor, flues below said floor for propagation of heating flames, pier walls for said oven dividing said oven 30 into a plurality of compartments, a conduit in each of said pier walls extending the length thereof, means for delivering gas to said conduit at one end of said pier walls and delivering gas from said conduit to said flues at the other end of said oven, said flues extending throughout the length of said floor, and means for selectively controlling the direction of gas flow through said conduit whereby to reverse the direction of flame propagation through said flues.

4. In an oven installation, in combination, a horizontal floor, flues below said floor extending longitudinally of said oven installation throughout the length thereof, pier walls for said oven installation, conduits extending through said pier walls longitudinally thereof, means for admitting gas to said flues, regenerator means for delivering air to said flues for mixture with said gas and for conducting products of combustion from said flues, said gas admitting means being located at the two ends of said oven installation, gas supply means connected to said conduits at both ends of said conduits, and valve means at each end of said conduits, said valve means being located between the corresponding gas supply means and the corresponding gas admitting means whereby the direction of gas flow through said conduits and the direction of flame propagation through said flues may be controlled.

5. In an oven, in combination, a horizontal floor, flues below said floor throughout the length

thereof, said oven having pier walls, a conduit extending through at least one of said pier walls longitudinally thereof, gas supply means connected to said conduit at the two ends of said oven, gas inlet means communicating with said flues at the two ends of said oven, regenerator means for delivering air to said flues for mixture with said gas and for conducting products of combustion from said flues, and valve means between said gas supply means and said gas inlet 10 means at each end of said oven for selectively connecting said gas supply means to said gas inlet means.

6. In combination, a battery of ovens, pier walls between the ovens of said battery, each of said ovens having a horizontal floor and heating flues below said floor extending throughout the length thereof, said pier walls being provided with passageways extending longitudinally thereof, and means for selectively directing gas through 15 said passageways in one direction or the other to one end or the other of said flues, said ovens having regenerative chambers cooperating with said flues for delivering air to said flues and for delivering products of combustion from said flues, 20 said passageways including portions in thermal communication with said chambers.

7. In combination, a battery of ovens, pier walls between the ovens of said battery, each of said ovens having a horizontal floor and heating flues below said floor extending throughout the length thereof, said pier walls being provided with passageways extending longitudinally thereof, and means for selectively directing gas through 30 said passageways in one direction or the other to one end or the other of said flues, said passageways being located at a level below said floors, said ovens having regenerative chambers cooperating with said flues for delivering air to said flues and for delivering products of combustion 35 from said flues, said passageways including portions in thermal communication with said chambers.

8. In combination, a battery of ovens, pier walls between the ovens of said battery, each of said ovens having a horizontal floor and heating flues below said floor extending throughout the length thereof, said pier walls being provided with passageways extending longitudinally thereof, and means for directing gas through said 40 passageways to said flues, said ovens having regenerative chambers cooperating with said flues for delivering air to said flues for mixture with said gas and for conducting products of combustion from said flues, said passageways having 45 looped portions connected to said gas directing means and disposed in thermal communication with said chambers.

MAURICE D. CURRAN.
